UNITED STATES PATENT OFFICE.

FRANK J. BLUM, OF DANSVILLE, NEW YORK.

DESIGN FOR A SLIPPER.

51,711.

Specification for Design.

Patented Feb. 5, 1918.

Application filed December 3, 1917. Serial No. 205,261. Term of patent 3½ years.

To all whom it may concern:

Be it known that I, FRANK J. BLUM, a citizen of the United States, and a resident of Dansville, in the county of Livingston and State of New York, have invented a new, original, and ornamental Design for Slippers, of which the following is a specification, reference being had to the accompanying drawing, forming part thereof.

Figure 1 is a top plan view of a slipper showing my new design; and,

Fig. 2 is a side elevation of the same.

I claim:

The ornamental design for a slipper, as shown.

FRANK J. BLUM.

Witnesses:

PHILIP E. BLUM,
JOHN R. BLUM.
